UNITED STATES PATENT OFFICE.

ELSWORTH E. QUAINSTANCE, OF DENVER, COLORADO, ASSIGNOR TO THE PERMUTATION LOCK AND NOVELTY MANUFACTURING COMPANY, OF DENVER, COLORADO.

AMUSEMENT APPARATUS.

No. 894,984.

Specification of Letters Patent.

Patented Aug. 4, 1908.

Application filed September 4, 1906. Serial No. 333,119.

To all whom it may concern:

Be it known that I, ELSWORTH E. QUAINSTANCE, a citizen of the United States, residing in the city and county of Denver 5 and State of Colorado, have invented certain new and useful Improvements in Amusement Apparatus; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

My invention relates to improvements in amusement apparatus, my object being to provide a device more especially adapted for use at amusement resorts and the same 20 will be fully understood by reference to the accompanying drawing in which,

Figure 1 is an elevation of the device partly in section. Fig. 2 is a fragmentary view illustrating a portion of the frame work. Fig. 3 is a fragmentary sectional detail view of one of the posts of the frame work shown on a larger scale. Fig. 4 is an underneath view of the central bottom plate with which the radial bottom frame bars are 25 connected, the same being shown on a larger scale. Fig. 5 is a sectional view of the construction shown in Fig. 4. Fig. 6 is a detail view of one of the revolving sweeps shown on a larger scale than in 30 Fig. 1. Fig. 7 is a detail view of a counter-weight which may be employed if desired. Fig. 8 is a section taken through the spring-actuated shaft above one of the ratchet gears which is shown in top plan view. 35 Fig. 9 is a vertical section taken through the construction shown in Fig. 8. Fig. 10 is a detail view of the representation of a horse and rider showing the manner of its mounting upon one of the sweeps, the parts being 40 shown on a larger scale than in Fig. 1. Fig. 45 Fig. 11 illustrates two details of construction. Fig. 12 is a top plan view of the construction shown in Fig. 1.

The same reference characters indicate 50 the same parts in all the views.

Let the numeral 5 designate a suitable frame work which comprises four posts A;

four bottom rods B, a top cross bar C and two tie wires or rods D and D'. The cross bar C at the top is connected with two of the 55 posts A by means of nuts E screwed upon threaded projections F applied to the top of each post. The tie rods D or wires D' as the case may be, may be connected with the posts in any suitable manner. In Fig. 2 60 the rod D is provided with an eye which slips over the threaded projection F at the top of the post and is held in place by a nut E while the wire D' is connected with a rod D' whose lower extremity enters the top of 65 the frame post and is held in place by a set screw D'. The inner extremities of the rod D and the wire D' are connected with the cross bar C in which the upper extremity of the central shaft 6 is journaled. 70

The bottom bars B are detachably connected with the post by means of bolts 7 held in place by thumb nuts 8, the extremities of the bars being inserted in socket projections 9 formed on sleeves 10 made fast 75 to the posts. The inner extremities of these bars are connected with a central plate 12 by means of depending clamps 13 made fast to the plate and secured to the bars by bolts 14 to which are applied thumb nuts 15. 80

The central shaft 6 has its lower extremity reduced as shown at 6^a to enter a sleeve 55 revolvably mounted in a casing 16 secured to the plate 12. The top of this casing is closed by a cap 16^a. Within this casing is located 85 a power spring 17, one extremity of which is secured to the casing as shown at 18, while its opposite extremity is made fast to the sleeve 55. The lower extremity of this sleeve is provided with a conical plug 19 which projects below the sleeve proper and enters a counterpart socket formed in the center of the plate 12 in order to allow the shaft to rotate freely. The lower extremity of the shaft 6 is secured to the sleeve 55 by a removable 90 key 58.

By virtue of the construction of the frame work as heretofore described, it is evident that the entire construction may be taken apart and packed into small compass for ease 100 of transportation.

To the upper extremity of the shaft 6 above the cross piece C is applied an operating crank 20 for winding the spring 17 or

placing the same under tension. Above the casing 16, a number of disks 21 is mounted upon the shaft 6. To the center of each disk is secured a drum 22 carrying ball bearings 23 held in place by ball cups 24. These balls engage cones formed on the shaft and allow the disks to rotate freely on the shaft by virtue of their momentum after the shaft has ceased to rotate under the influence of the power spring. The upper and lower extremities of the drum are closed by top and bottom plates 25 and 26 which are fast on the shaft. The lower plate 26 forms a support for the drum and its disk. Upon the upper surface of each disk 21, is formed ratchet teeth 27 adapted to be engaged by a pawl 28 pivotally mounted between two lugs 29 carried by a projection 30 formed on a collar 31 made fast to the shaft 6 by a set bolt 32. The disk 21 is provided with lateral projections 21^a located on opposite sides thereof. To these lateral projections are detachably connected the sweeps 33 whose inner extremities are bent downwardly as shown at 34^a and enter openings formed in the projections 21^a. The outer extremity of each projection is provided with two lugs 21^b between which the sweep 33 rests. The body portion 33 of each sweep is provided with a strengthening brace 33^a, suitably connected with the body of the sweep as shown at 33^b and 33^c. The outer extremity of each sweep is turned upwardly as shown at 33^b and to the upper extremity of each part 33^b is secured a collar 34 provided with a lateral projection 35. To each of these sweep extremities, is detachably applied an image 36 preferably the representation of a horse in the racing attitude and shown in connection with a rider dressed in the costume of a jockey (see Fig. 10). This image is made fast to a bracket 37 provided with a socket or sleeve 38 which the upper extremity of the sweep part 33^b enters. This bracket is also provided with a lateral projection having two separated lugs 37^a adapted to straddle the part 35 whereby the image is connected with the sweep in such a manner that it is caused to travel or rotate therewith.

In order that each sweep may be equipped with a retarding device or a brake whose tension is adjustable, each projection 30 is provided with a leaf spring 39 secured to an upwardly projecting lug 40 of the arm 30. This spring extends inwardly from the lug and is adapted to bear upon the adjacent drum 22. Its tension is regulated by means of a set screw 41 threaded in an upwardly projecting lug 42, the inner extremity of the set screw bearing upon the spring and serving to force it against the drum when the screw is properly adjusted. By means of this construction, the tension of the various springs may be made to vary, thus causing a varia-

tion in the travel of the disks, the sweeps and the images carried thereby, by virtue of their momentum, after the shaft has ceased to rotate.

As shown in the drawing the uppermost disk 21, carries but one sweep 33. In this case it is desirable in order that the structure may be well balanced, to apply a counterbalance weight 43 to the opposite side of the disk or to the opposite lug 21^a. This weight is provided with an angular arm 43^a which enters an opening formed in the said lug, and passes between the lugs 21^b of the projection, whereby the counterpart is held in place. Each of the disks below the uppermost, is equipped with two sweeps 33, the same being respectively attached to the laterally projecting lugs 21^a located on opposite sides of the disk.

The operating mechanism mounted on the power shaft 6, together with the sweeps except their upper portions, are concealed from exterior view by means of a piece of canvas or other suitable material 44 which may be secured to the posts of the frame in any suitable manner. As shown in the drawing, the upper and lower edges of this canvas are attached to metal rings or bands 45 provided with ears 46 through which are passed bolts 47. These bolts are also passed through the frame posts and secured by nuts on the outside. By means of this construction the canvas is securely held in place at the top and bottom, but may be readily detached by removing the bolts.

The lower extremity of each frame post A is detachably connected with the body of the post. As shown in the drawing this part A' is provided with a screw protruding from its upper extremity, the head of said screw being embedded in the plug A² inserted in the top A'. This screw protrudes above the top of the last named part and is adapted to enter a threaded opening formed in the block or top 48 inserted in the lower extremity of each post A. The removal of these post extremities, further facilitates the reduction of the frame work to small compass for purposes of transportation.

To the top frame beam, on one side of the shaft is applied a small casing 49 inclosing a coil spring 50. In this casing is slidably mounted a dog or pawl 51 connected with a rod 52. This spring normally holds the dog 51 in the position protruding inwardly from the casing and into the path of the hand crank 20, whereby the dog forms a stop to prevent the unwinding of the spring 17 after the latter has been placed under tension.

Assuming now that the power spring has been wound by the rotation of the shaft 6 through the instrumentality of the hand crank 20, as soon as its crank is released by the operator, the dog 51 acts as a stop to pre-

vent the unwinding of the spring and the rotation of the shaft acting thereon. As soon, however, as it is desired to set the sweeps in motion, the operator pulls outwardly upon the operating rod 52, and releases the hand crank, allowing the power shaft 6 to rotate under the influence of the power spring 17. As the power of the spring acts upon this shaft, the sweeps may be caused to rotate more or less readily according to the strength of the spring. While the shaft is rotating, the pawls 28 acting on the ratchet teeth of the disks, carries the said disks and their attachments around. During the rotation of the shaft the various sweeps together with the images thereon should normally maintain the same relative position in which the start was made. However, as soon as the shaft ceases to move, the sweeps and their connections, will continue their movement a certain time by virtue of their acquired momentum. By proper regulation of the tension springs 39, the movement of the sweeps may be retarded in varying degrees, whereby some of the images or figures will travel more rapidly than the others.

In using the apparatus it is the intention to have the horses or other devices 36, designated by different numbers, colors or names. In this event those who wish to participate in the amusement, may choose different horses, and the horse that stops nearest the wire D' on the approaching side when going in the direction indicated by the arrow in Fig. 12, wins the game or is entitled to a cigar or other premium which the management of the apparatus may choose to offer. The wire D' is employed in preference to a rod, for the reason that it permits a closer calculation of the relative positions of the various horses when they cease to move. It will be understood that under the influence of the power spring acting on the shaft 6, the horses being connected with the outer extremities of the sweeps, will acquire considerable speed and will necessarily continue to move after the shaft has stopped. As soon as this movement commences, the ratchet disks must of course slide under the pawls 28 which while the shaft is moving, propels the disks. During this movement by momentum, it is assumed that the different horses will move at different rates of speed, or in other words that they will change their relative positions upon the apparatus.

From an inspection of the drawing (see Fig. 1), it will be observed that while the operating disks are mounted one above another and surrounding the power shaft 6, the outer extremities of the sweeps, are bent upwardly to travel in different circles, whereby the horses mounted above their upper extremities, may all be arranged side by side.

By virtue of this arrangement the horses are all traveling in the same plane, but in different circles or paths, whereby one cannot in any way or under any circumstances interfere with the travel of the other.

From the description already given, the manner of taking the construction apart whereby it may be packed into small compass, will be readily understood and need not be described further in detail.

Having thus described my invention, what I claim is:

1. In amusement apparatus, the combination with a suitable frame, of a spring-actuated power shaft, sweeps carrying figures, an operative ratchet and pawl connection between the shaft and the sweeps whereby the latter are caused to rotate with the shaft but permitted to travel around the latter after it has ceased to move, and an individual retarding device or brake for each sweep.

2. In amusement apparatus, the combination with a suitable frame work, of a spring-actuated power shaft, ratchet disks loosely mounted on the shaft one above the other, pawls carried by the shaft for operating the disks, sweeps of different length connected with the disks, the sweeps carrying devices at their outer extremities, and an individual retarding device for each disk.

3. In apparatus of the class described, the combination with a suitable frame work, of a spring-actuated power shaft, ratchet disks loosely mounted on the power shaft one above another, pawls carried by the said shaft for actuating the disks, an individual retarding device for each disk, and sweeps detachably connected with the respective disks.

4. The combination with a suitable frame, of a spring-actuated power shaft journaled in the frame, sweeps, a ratchet and pawl connection between the shaft and the sweeps, a crank connected with the power shaft, and a spring-actuated crank stop slidably mounted on the frame work and normally occupying a position in the path of the crank.

5. The combination with a knock down frame, of a centrally located spring-actuated power shaft journaled in the frame, sweeps carrying figures, an operative ratchet and pawl connection between the sweeps and the shaft whereby the sweeps are propelled by the shaft but allowed to continue movement by momentum after the shaft has ceased to move, and an individual retarding or brake device for each sweep.

6. In amusement apparatus, the combination of a frame work composed of upright posts, radial bars located at the bottom and having their outer extremities detachably connected with the post, a centrally located plate with which their inner extremities are detachably connected, a top cross bar detachably connected with the upper extremi-

ties of two of the posts, means connecting the other two posts at the top with the cross bar, a centrally located spring-actuated power shaft journaled in the cross bar at the top and in the said plate at the bottom, and sweeps connected with the shaft in operative relation for the purpose set forth.

In testimony whereof I affix my signature in presence of two witnesses.

ELSWORTH E. QUAINSTANCE.
